CLAIM

The ornamental design for a hanging chair bracket, as shown and described.

DESCRIPTION

FIG. 1 is a front and right perspective view of a hanging chair bracket, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an enlarged view of an area labeled 8 in FIG. 1.

FIG. 9 is an enlarged view of an area labeled 9 in FIG. 1; and,

FIG. 10 is an enlarged view of an area labeled 10 in FIG. 1. The broken lines are for environmental structure, boundaries, or illustrative purposes only and form no part of the claimed designs to be patented.
